UNITED STATES PATENT OFFICE.

ARTHUR E. PECK, OF MINNEAPOLIS, MINNESOTA.

TOOTH-BRUSH GUARD.

1,186,330.

Specification of Letters Patent. Patented June 6, 1916.

Application filed May 13, 1913. Serial No. 767,306.

To all whom it may concern:

Be it known that I, ARTHUR E. PECK, a citizen of the United States, resident of Minneapolis, county of Hennepin, State of Minnesota, have invented certain new and useful Improvements in Tooth-Brush Guards, of which the following is a specification.

Tooth brushes are generally kept with other toilet articles, exposed to the open air and to dust and disease germs. The wet bristles after use of the brush will collect the dust and other foreign matter floating in the air and the usual rinsing of the brush will fail to thoroughly clean the bristles before or after use.

The object of my present invention is to provide a guard which will effectually cover and protect the brush bristles, preventing the accumulation of dust and foreign matter thereon and keeping the bristles clean and ready for immediate use at any time.

A further object is to provide a means in connection with the guard which will enable the user of the brush to thoroughly scrape and clean the bristles and remove any foreign matter which may be between them.

The invention consists generally in a guard, all as hereinafter described and particularly pointed out in the claims.

In the accompanying drawings forming part of this specification, Figure 1 is a perspective view of a guard embodying my invention, Fig. 2 is a side view of a brush with my invention applied thereto, the guard being shown in section to illustrate the manner of concealing and protecting the bristles, Fig. 3 is a view looking toward the ends of the bristles, showing the guard covering and concealing the same, Fig. 4 is a view, illustrating the manner of using the device for cleaning the bristles.

In the drawing, 2 represents a tooth brush handle having bristles 3 mounted therein. The guard which I prefer to employ consists of a back plate 4 having inwardly turned side wings 5 parallel substantially with one another and provided on their edges with lugs 6. A space is formed between the wings 5 to receive the brush bristles, the back of the brush closing the space between the wings and having its end portion fitting into an opening 7 provided between the lugs 6 and the end wall 8, which extends across the guard between the wings. This end wall

may be formed separately and secured to the 55 wings. At the opposite end of the guard from the wall 8 is a flange 9 which may be formed by bending the end portion of the back plate upwardly to close the space between the wings at that end of the guard, 60 and this flange preferably terminates in a fork 10 having its teeth bent upwardly in a plane, parallel, substantially, with the back plate. The fork 10 bears on the back of the brush near the heel thereof and cooperates with the wall at the point of the brush to aid in holding the guard in place over the bristles. The opening between the flange 9 and the lug 6 is unobstructed and sufficiently large to allow the insertion of 70 the end of the brush therein, the wings having their edges flared slightly to guide the ends of the bristles into the space between the wings.

As plainly shown in Figs. 3 and 4, the 75 guard tapers slightly toward its outer end and the space between the wings is gradually contracted to allow the point of the brush to be thrust in between the lug 6 and the wall 8 and be held by the frictional engagement 80 of the back of the brush with the walls of the wings and the lugs. When the guard is in place, the bristles will be concealed and protected and the brush may be carried in the pocket or in a traveling case, or may be 85 exposed with other toilet articles without danger of accumulating dust or sediment from the air. Whenever necessary, the bristles may be easily and quickly cleaned, as indicated in Fig. 4, by inserting the fork 90 into the base of the bristles and moving it outwardly thereon.

I claim as my invention:—

1. A tooth brush guard comprising a back plate and side walls formed on the edges 95 thereof, a space being provided between said walls to receive the bristle end of the brush, overhanging said space and an end wall between said side walls, a space being provided between said lugs and said end wall to receive 100 the end of the brush back, said back resting on said end wall and being wedged between it and said lugs.

2. A tooth brush guard comprising a back plate and side and end walls therefor, said 105 guard being open on one side to allow the insertion of the bristle end of the brush therein, the space between said side walls

gradually decreasing in width from the inner toward the outer end of said guard, said side walls having means between which and one end of said end walls the back of the brush is wedged.

3. A tooth brush guard having a part to cover the ends of the bristles and a cleaning fork provided at one end of the guard and including prongs adapted to be inserted 15 into and between the bristles when the guard is removed from over the bristles.

4. A tooth brush guard having a part to cover the ends of the bristles, and a cleaning fork provided at one end of the guard 15 and adapted to be seated against the handle of the brush near the heel thereof when said guard is over the bristles, said cleaning fork including comparatively narrow tines spaced apart and adapted when said guard is 20 removed from over said bristles to be inserted between the bristles of the brush.

5. A tooth brush cleaning device adapted to be mounted on the brush handle and having means for insertion between the bristles

of the brush when removed from the handle.

6. A sheet metal guard for a tooth brush comprising a back plate and side walls and means for holding the guard in place on the bristle end of the brush, and a fork adapted 30 to lie on the brush handle adjacent to the heel of the brush when said guard is over the bristles and comprising narrow tines adapted for insertion between the bristles of the brush when said guard is removed from 35 over said bristles.

7. A tooth brush guard adapted to cover the ends of the bristles and having means adapted to be inserted between the bristles when the guard is removed from over the 40 bristles.

In witness whereof, I have hereunto set my hand this 5th day of May 1913.

ARTHUR E. PECK.
